UNITED STATES PATENT OFFICE.

FRED W. CROSBY, OF GARNETT, KANSAS.

DOOR-OPERATING MECHANISM.

1,421,177.

Specification of Letters Patent. Patented June 27, 1922.

Application filed November 1, 1920. Serial No. 421,067.

To all whom it may concern:

Be it known that I, FRED W. CROSBY, a citizen of the United States, residing at Garnett, in the county of Anderson and State 5 of Kansas, have invented certain new and useful Improvements in Door-Operating Mechanisms; and I do declare the following to be a full, clear, and exact description of the invention, such as will enable 10 others skilled in the art to which it app pertains to make and use the same.

My invention relates to door operating mechanisms and more particularly to those which are designed primarily for use on 15 garages and the like, to be self-opening as a vehicle approaches, whereby such vehicle may be driven into the building without the necessity of the driver leaving the same to open the door.

20 The principal object of my invention is to provide a novel door operating mechanism which is operated by compressed air, novel provision being made whereby such air normally acts to hold the door in closed position, but is automatically released upon the approach of a vehicle, whereupon a series of weights and a cable come into play to open the door, one of said weights serving to again place the door closing 25 30 means in an operative condition, whereby to return the door to closed position.

With the foregoing in view, the invention resides in the novel construction and combination of parts hereinafter described and 35 claimed, the descriptive matter being supplemented by the accompanying drawings.

Figure 1 is a vertical sectional view of 40 a garage showing the application of my invention to a sliding door thereof, the door being shown in closed position.

Figure 2 is a view similar to Fig. 1 but showing the door in the act of opening.

Figure 3 is a sectional view similar to Figs. 1 and 2, showing the door in completely opened position.

Figure 4 is a horizontal sectional view as indicated by line 4—4 of Fig. 3.

Figure 5 is a detail transverse section on the plane designated by line 5—5 of Fig. 3.

50 Figure 6 is a vertical transverse sectional view as indicated by line 6—6 of Fig. 1.

Figure 7 is a detail horizontal sectional view taken on line 7—7 of Fig. 1.

In the drawings above briefly described, 55 the numeral 1 designates a garage or other building having a door opening 2 and a

door 3 for closing said opening, said door being slidably mounted on suitable hangers 4 and a horizontal track 5. A compressed air cylinder 6 is rigidly secured to the inner side of the door 3 and is positioned horizontally, said cylinder having therein a relatively fixed piston 7 which is carried by the end of a compressed air supply pipe 8, which pipe may be rigidly mounted in any 60 preferred manner and may well lead from a compressed air tank 9, although any other suitable source of air pressure could be utilized. The end of the cylinder 6 is preferably enlarged as seen at 10 and is closed 65 by a head or cap 11, the latter being provided with an air escape opening 12 and a preferably pivoted valve 13 for normally closing said opening, whereby the air entering the cylinder between the piston and the 70 cylinder head will act to close the door 3. I make provision however for opening the valve 13 when a vehicle approaches the 75 garage whereby the air may escape from the cylinder 6, and a novel arrangement of parts 80 is employed for then opening the door.

The valve opening means might assume numerous forms, but for illustrative purposes, I have shown a vertically movable rod 14 slideable in appropriate bearings 15 85 carried by the building 1 and normally depressed by means of a coiled spring 16. When the door is closed, a lateral arm 17 on the pivoted valve 13 overlies the rod 14 as shown clearly in Fig. 1 and it thus follows that if this rod is raised, the valve will be turned on its pivot 18 and moved to an open position, so that the air may escape 90 from the cylinder 6 and allow the door 3 to open. For raising the rod 14, I have shown a horizontal lever 19 which may be inset in 95 the approach to the garage door, the inner end of said lever underlying the aforesaid rod, while the outer end thereof is equipped with a cross arm or the like 20 to be depressed by the vehicle wheels as will be clear 100 from the dotted lines of Fig. 4. It will be seen that as soon as the lever 19 is rocked by depression of this cross arm 20, the rod 14 is raised against the tension of the spring 16, thereby opening the valve 13 and permitting the escape of air from the cylinder 105 6, so that the door opening means may come into play. The moment the door starts on its opening movement, the spring 16 returns 110 the rod 14 and the lever 19 to their initial positions and if desired, this spring may

be of such tension that the weight of a person on the cross arm 20 would not rock the lever 19 to raise the aforesaid rod. It may thus be insured that unauthorized persons 5 shall not enter the garage by this means.

For opening the door 3 after release of the compressed air from the cylinder 6, I provide a cable 25 having a counterbalancing weight 26 of sufficient size to open the 10 door when said weight is allowed to descend by gravity. This weight, when the door is closed, stands in an elevated position as seen in Fig. 1 but lowers as indicated by the arrow in Fig. 2, for the purpose of opening the 15 door. The cable 25 passes around suitable guides 27 which are fixed with respect to the door 3 and the end of said cable remote from the weight 26 passes over a guide or pulley 28 which is movable bodily with said 20 door, being preferably carried by an appropriate bracket 29. Below the pulley, the bracket 29 is provided with a cable guide or eye 30 through which the free end of the cable 25 passes, said end being provided with 25 a relatively light weight 31 which normally abuts said eye so that an operative connection is established between the cable and the door for the purpose of opening the latter as the weight 26 descends. It will be ob- 30 served by reference to Figs. 1 and 2, that the weight 31 is in vertical alignment with the lateral arm 17 of the air release valve 13. It will be further observed by comparing Figs. 1, 2 and 3, that after the weight 26 35 has lowered to the maximum to partly open the door 3, the weight 31 then descends to complete the opening movement of said door. By the time the door is completely opened, the weight 31 strikes the arm 17 and thus 40 closes the valve 13. The compressed air passing through the pipe 8 into the cylinder 6 then becomes effective to slowly start the door 3 on its closing movement, but before said door has moved appreciably, the vehicle 45 is within the garage and the door may close uninterruptedly. When in completely closed position, the door stands as seen in Fig. 1, with the arm 17 again overlying the rod 14 to be tripped by the next machine approaching 50 the building. If the door 3 is to be opened from the inside of the garage, the valve 13 may well be opened by hand, whereupon the weights and cable will come into play to open the door as above set forth.

55 Although the operation of the invention will probably be understood from the foregoing, it may be well to give a brief explanation thereof, and to this end, we will assume that the door 3 stands closed as seen 60 in Fig. 1 with the arm 17 of the valve 13 overlying the rod 14. When now a machine or other vehicle approaches the garage door, the wheels strike and depress the cross arm 20, thereby rocking the lever 19 and raising 65 the rod 14, with the result that said rod acts

on the arm 17 to open the valve 13. This permits the escape of the previously entrapped compressed air from the cylinder 6, whereupon the weight 26 immediately descends and pulls upon the cable 25 to slide 70 the door 3 toward an open position (see Fig. 2). When the weight 26 reaches the floor of the building or any other appropriate stop, the lighter weight 31 descends and completes the opening movement of the door, 75 said last named weight eventually striking the arm 17 and serving to close the valve 13. In the meantime, the vehicle has entered the garage and as the compressed air from the tank 9 now acts on the cylinder 6 and piston 7 to again close the door, such closing will not be interfered with. As the door closes, the weight 31 first returns to its normal position and then the cable 25 is pulled upon to raise the weight 26 to the elevated 80 position of Fig. 1 so that it is again in condition for use.

I claim:

1. In combination, a door frame, a door 90 slideable toward one vertical side of said frame, a vehicle-operated valve-opening member stationarily mounted at said side of the frame, a horizontal fluid pressure cylinder rigidly mounted on said door and having an air escape opening in the end adjacent said side of the frame, a valve carried bodily by said cylinder for normally closing said opening, means for supplying fluid pressure to said cylinder, a fixed piston within said cylinder whereby the fluid pressure will act to force the door toward said side of the frame and close the same, said valve having an operating part in operative relation with said valve opening member when said door is closed, whereby operation of 95 said member will open said valve and release the air from said cylinder, means for automatically opening the door when the fluid pressure is released, and normally raised downwardly movable means automatically 100 operable to engage said valve operating part and close the valve when the door is completely opened.

2. In combination, a frame, a door slideable toward one side of said frame to closed 115 position, a normally lowered vehicle-raised valve-opening member stationarily mounted at said side of the frame, a horizontal fluid pressure cylinder rigidly mounted on said door and having an air escape opening in the end adjacent said side of the frame, a valve member pivoted to said end of the cylinder and closing said opening when the door is in closed position, said valve member having a lateral projection which 120 overlies said valve-opening member when the door is closed, whereby raising of said member will open the valve to permit escape of fluid pressure from the cylinder, a fixed piston in said cylinder and means asso- 125 130

ciated therewith for supplying fluid pressure to the cylinder, together with normally raised means movable with the door and positioned above said projection of said valve member, said last named means being adapted to lower by gravity when the door is completely opened, whereby to strike said projection and again close said valve member.

3. The combination with a passage and a door therefor; of means for holding said door in closed position by air pressure, said holding means having a pressure release valve movable bodily with said door, a cable connected with said door and having a counterbalancing weight for opening the door when said pressure release valve is opened, said counterbalancing weight having limited downward movement, and a relatively light weight attached to the aforementioned cable and adapted to descend when the action of said counterbalancing weight ceases, said relatively light weight being adapted to close said pressure release valve as it descends.

4. The combination with a passage and a door therefor; of means for holding said door in closed position by air pressure, said holding means having a pressure release valve movable bodily with said door, a cable guide carried by said door above said pressure release valve, a cable trained over said cable guide at one end, a counterbalancing weight connected with the other end of said cable for partially opening the door when said pressure release valve is opened, said counterbalancing weight having limited downward movement, and a relatively light weight on the first named end of said cable adapted to lower and complete the opening movement of the door when said counterbalancing weight has reached the limit of its downward movement, said relatively light weight being adapted to strike and close said pressure release valve when the door is completely opened.

In testimony whereof I have hereunto set my hand.

FRED W. CROSBY.
